WILLIAM R. WARNER, OF PHILADELPHIA, PENNSYLVANIA, ASSIGNOR TO
WILLIAM R. WARNER & CO., OF SAME PLACE.

Design No. 4,745, dated March 28, 1871.

DESIGN FOR A GLASS BOTTLE.

The Schedule referred to in these Letters Patent and making part of the same.

I, WILLIAM R. WARNER, of Philadelphia, county of Philadelphia, State of Pennsylvania, have invented or produced a Design for a Glass Vessel or Bottle, of which the following is a specification.

In the accompanying drawing—

Figure 1 is a perspective view of a glass vessel or bottle made in accordance with my design.

Figure 2, a side view of the same.

The upper portion or body A of the vessel is of a spherical or nearly spherical form, and the said body is connected by a neck or stem, B, to a flange, C, which forms an extended base for the support of the vessel.

The body A and stem B are hollow, and the latter is provided with a cork or stopper.

The whole vessel presents an ornamental appearance, and the spherical body, owing to its elevated and

unobstructed position, enables the contents of the same to be displayed to the best advantage.

The extended base presents a convenient surface upon which to mark letters or figures designating the character of the contents of the vessel, without obstructing the view of the interior of the latter.

Claim.

The design for a glass vessel or bottle, substantially as described and as represented in and by the accompanying drawing.

In testimony whereof I have signed my name to this specification in the presence of two subscribing witnesses.

Witnesses: WILLIAM R. WARNER.
